UNITED STATES PATENT OFFICE.

JOHN ROVANE, OF KEOUK, IOWA.

ROLL-PAPER HOLDER AND CUTTER.

SPECIFICATION forming part of Letters Patent No. 429,548, dated June 3, 1890.

Application filed April 29, 1889. Serial No. 309,080. (No model.)

To all whom it may concern:

Be it known that I, JOHN ROVANE, of Keokuk, in the county of Lee and State of Iowa, a citizen of the United States, have invented 5 a new and useful Improved Roll-Paper Holder and Cutter, which is made and used substantially as set forth hereinafter, and as shown in the accompanying drawings, in which—

Figure 1 is a perspective view of the apparatus. Fig. 2 is a cross-section showing details. Fig. 3 is an end elevation showing modification. Fig. 4 is a detail of modification, and Fig. 5 is a detail of another modification.

15 This invention relates to a roll-paper holder and cutter; and it consists in an improved system of parts and in several parts and features therein, as shown and as set forth.

The frame A bears roll D, the knife K, and 20 other parts, and is supported on the base B.

Paper for wrapping and other purposes is wound as a continuous sheet into a roll D on a central stock F, which turns freely on the central shaft E for use, as desired. The knife 25 K is located along the side of roll D, so that the paper when drawn off to the desired extent may be torn off against it by an upward draw. The roll and knife are arranged to bear against each other with pressure to cause 30 friction as a brake on the unrolling of the paper and in tearing it off. The knife is fixed in such relative position that the end of the paper may be readily grasped thereat and drawn off by hand.

35 Fig. 1 shows the roll D as hung upon the stirrup-hangers G from shaft H, which is hinged in frame A, so as to swing thereon and bear on the knife K, as further shown in Fig. 2. The shaft H bears a stiff coil-spring

40 I to cause the roll to bear against the knife K. The knife K is borne on a stirrup-frame L L', (shown in Figs. 1 and 2,) and its position is adjusted and held by a ratchet M on shaft L and pawl N on plate P. These are 45 arranged so that the position of the knife may be adjusted and held so that the roll will rest against it by both gravity and spring-pressure, or by the latter alone by means of handle R.

The stirrup-arms L add something to the spring-pressure.

50 Fig. 3 shows a modification where the shaft E of roll D is hung in bearings in frame A, the knife K being held against the roll by the motion of the stirrup-frame L and by the turning of wheel M on shaft L by handle R 55 until the pawl N falls into the proper tooth of the wheel to hold it at the desired tension. This tension may be readjusted whenever it becomes too weak by use.

Fig. 4 shows the mode of applying a spring 60 to hold the knife against the roll. The spring-coil S is borne by shaft L from arm L' to wheel M, which is mounted on shaft L, so as to turn thereon to wind up the spring, as desired.

65 Fig. 5 shows another modification, where the roll is held as in Figs. 1 and 2, and the knife is held in a fixed position by set-screw J in frame A.

Further modifications may be made.

I claim—

1. A roll-paper holder and cutter having the roll D, the knife K, resting against the roll, the pawl and ratchet N M, and handle R, substantially as set forth.

2. In a roll-paper holder and cutter, the combination of the roll D, knife K, pawl and ratchet M N, and the spring S, substantially as set forth.

3. The roll-paper holder and cutter having 80 a frame, a roll with swinging hangers, a cutter-bar resting against the roll and provided with a holding-shaft having a pawl and ratchet adjusting and holding apparatus.

4. A roll-paper holder and cutter having a 85 frame, a knife having an adjustable relation to the paper-roll, a crank on a shaft bearing a knife and its supports and provided with a pawl and ratchet, a means of fixed adjustment between said roll and said knife, and a spring adapted to supplement said fixed adjustment to a certain limited extent.

JOHN ROVANE.
